UNITED STATES PATENT OFFICE.

JEROME R. GEORGE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

ROLLING MILL.

Application filed July 9, 1923. Serial No. 650,381.

- The present invention relates generally to rolling mills. The invention resides in a novel disposition of the stands of rolls in a continuous or semi-continuous merchant mill, 5 in combination with a special arrangement of driving instrumentalities therefor, all contributing to a greater flexibility and a wider range of selective operation than has heretofore been possible in mills of this class.
- 10 The features and advantages of the invention are fully set forth in the following description, reference being had to the accompanying drawing, in which the single figure is a diagrammatic plan view of rolling mill apparatus combined and arranged in accordance with the invention.
- Referring to said drawing, the preliminary reduction of the stock, as received from a heating furnace 1, is preferably effected by 20 a pair of adjacent stands of rolls 2, 2, arranged for continuous operation and delivering onto a suitable mill runout 3, which preferably extends forwardly a sufficient distance to receive the full length of each piece delivered by said rolls 2, 2, so that the latter's operation is independent of and unrelated to the operation of the subsequent roll stands at the far end of said runout.
- Said subsequent stands of rolls, to which 30 the initially reduced stock is delivered from runout 3, are here shown as adjacent pairs of two-high roll stands 4, 4 and 5, 5. The stands 4, 4, arranged for continuous operation, are preferably driven through suitable gearing 35 from the same source of power as the roll stands 2, 2, as for instance, an adjustable speed electric motor 6, with interposed reduction gearing 7 to obtain the required low speeds. On the other hand, the roll stands 5, 5, are 40 ranged to operate substantially continuously with reference to the stands 4, 4, are driven from an independent source of power, namely, as here shown, the separate and distinct adjustable speed electric motor 8. In other 45 words, each piece of stock delivered by the second roll stand 4 invariably enters its first end in the first roll stand 5 before its rear end leaves said second roll stand 4. The two sets of roll stands 4, 4 and 5, 5 constitute, as above 50 described, the second section of the continuous grouping of the mill, and are preferably provided with a plurality of independent rows of differently shaped passes, to give such variety as may be desired in the cross section of the reduced material emerging therefrom. 55 Said material, as thus brought to an intermediate stage in its fabrication by a series of continuous rolling operations, is thereafter subjected, to any extent desired, to further reduction and elongation, through the medium 60 of independent open roll stands, arranged and operating in the following manner:—
- A Y-transfer conveying mechanism 9 of well known construction receives the stock from the roll stands 5, 5, and provides the usual 65 means, in the form of skewed conveyor rolls 10, 10, for effecting the travel of each piece as received thereon in the opposite direction, so as to present the rear end of said piece to the 70 pass of a stand of open rolls 11 which are offset from the continuous part of the mill. The rolls of stand 11 are rotated in the opposite direction from the preceding rolls by means of suitable gearing connecting them preferably with the adjustable speed electric motor 75 8, and each piece, as received thereby from the Y-transfer conveying mechanism 9, is projected onto a second oppositely arranged similar Y-transfer conveying mechanism 12, whose skewed conveyor rolls 13 procure the 80 resumption of the forward travel of the piece, with its front end foremost.
- Each piece is thus forwarded, for such further reduction as may be contemplated, to the stands of open rolls 14, 15 and 16, 85 any one of which is selectively available for finishing, in advance of projecting the pieces onto a runout 17, for delivery to a cooling bed or other receiving device, not shown. The stand of rolls 14 is preferably driven 90 by suitable gearing from the adjustable speed electric motor 8, while the stands 15 and 16 are driven respectively by suitable independent motors 19 and 20, so that, while the tandem arrangement makes the three 95 stands susceptible of operation in a continuous manner whenever desired, there is no obstacle to the formation of free loops in the material, as indicated, for example, at 21 and 22, and no handicap to the flexibility, 100 and capacity for selective operation, which characterizes the arrangement.
- It is to be noted that the apparatus, as above described, possesses all the advantages 105 of the ordinary continuous mill, while at the same time eliminating the limitations on

flexibility and other disadvantages that such a mill usually must work under. By reason of dividing the drive of the continuously arranged stands 4, 4, 5, 5 there is no sacrifice of flexibility in this part of the mill, since by such arrangement, the number of roll stands that are mechanically geared together with fixed speed relations between them is limited in every case to two.

19 In other words, the fact that the two roll stands 5, 5, while disposed in "continuous" relation to the two roll stands 4, 4, are nevertheless independently driven, gives opportunity for wide variations in the draft 15 which, under any given set of circumstances, it may be desired to have the stands 5, 5 exert on the stock in process of reduction.

For example, the draft of either or both of the two stands 5, 5 may be varied between 20 zero and a maximum, depending upon the requirements of the particular kind of stock that is undergoing reduction; in the absence altogether of any reducing action by either or both of these two stands 5, 5, any stock 25 that undergoes sufficient roughing reduction in the preceding stands 2, 2 and 4, 4 can still be run out on the conveying mechanism 9, preliminary to its finishing by the non-continuous or open stands 11, 14, 15 and 16. 30 Other stock may require more or less roughening reduction, and this requirement can readily be satisfied by making either or both of the stands 5, 5 effective, to any desired extent, for rolling in "continuous" relation 35 to the stands 4, 4.

I claim:

1. In a rolling mill, a plurality of alined stands of rolls arranged in juxtaposition for continuous operation with less spacing between said stands than the length of the stock passing therethrough, one group of said alined continuous stands being actuated from the same source as preceding rolls of said mill and another group of said alined 45 continuous stands being actuated from the same source as succeeding non-continuous or open roll stands of said mill.

2. In a rolling mill, a plurality of alined stands of rolls arranged in juxtaposition for 50 continuous operation with less spacing between said stands than the length of the stock passing therethrough, other stands of rolls arranged in preceding and succeeding non-continuous relation to said alined continuous stands, and roll actuating means common to said preceding stands and to a portion only of said alined continuous stands.

3. In a rolling mill, a plurality of alined stands of rolls arranged in juxtaposition for 60 continuous operation with less spacing between said stands than the length of the stock passing therethrough, other stands of rolls in preceding and succeeding non-continuous relation to said alined continuous stands, and 65 roll actuating mean common to said succeed-

ing stands and to a portion only of said alined continuous stands.

4. In a rolling mill, a plurality of alined stands of rolls arranged in juxtaposition for continuous operation with less spacing between said stands than the length of the stock passing therethrough, other stands of rolls in preceding and succeeding non-continuous relation to said alined continuous stands, a roll actuating means common to said preceding 70 stands and to a portion only of said alined continuous stands, and a second roll actuating means common to said succeeding stands and to the remainder of said alined continuous stands. 75

5. In a rolling mill, a plurality of alined stands of rolls arranged in juxtaposition for continuous operation with less spacing between said stands than the length of the stock passing therethrough, an actuating means common to a portion only of said alined continuous stands and to preceding non-continuous stands of the mill, and an independent adjustable speed electric motor for driving the remainder of said alined continuous 80 stands. 85

6. The combination, with the roll stands of a roughing mill, of a plurality of alined roll stands arranged in juxtaposition for continuous operation on the product of said roughing mill, with less spacing between adjacent stands than the length of said product, a common actuating means for the roll stands of said roughing mill and one group of said alined continuous stands, and independent actuating means for another group of said alined continuous stands and for the succeeding open or non-continuous finishing stands of said mill. 90 95

7. The combination with a plurality of alined roll stands arranged in juxtaposition for continuous operation with less spacing between said stands than the length of the stock passing therethrough, of a plurality of open roll stands for operation on the product of said continuously arranged stands, and a common actuating means for said open stands and a next preceding group, less than the whole number, of said alined continuous stands, to drive them independently of others 100 105 of said alined continuous stands. 110

8. A rolling mill having a plurality of pairs of stands of alined rolls, arranged in juxtaposition for continuous operation, with less spacing between said pairs than the length of the stock passing therethrough, followed by at least three stands of open rolls, with the last pair of stands of continuous rolls and the next two stands of open rolls actuated independently of the other roll 115 120 stands of said mill. 125

9. A rolling mill consisting of eight or more stands of two-high rolls, with the last three stands arranged in tandem for continuous operation, the next preceding single 130 135

stand for independent operation, and the stands next preceding said single stand for continuous operation, said last-mentioned stands being spaced apart from each other by less than the length of the stock passing therethrough and being divided into two independently actuated groups.

10. A rolling mill consisting of eight or more stands of two-high rolls, with the last three stands arranged in tandem for continuous operation, the next preceding single stand

for independent operation, and the stands next preceding said single stand for continuous operation, with the spacing between said continuously arranged stands less than the length of the stock passing therethrough and an independent common actuating means for a pair of said last-mentioned continuous stands, said single stand, and one of the last three stands.

Dated this 27th day of June, 1923.

JEROME R. GEORGE.
